MULTISTREAM ANALYZER WITH STREAM SWITCHING APPARATUS

Dale E. Lupfer and Ernest D. Tolin, Bartlesville, Okla., assignors to Phillips Petroleum Company, a corporation of Delaware

Application September 10, 1954, Serial No. 455,120

11 Claims. (Cl. 88—14)

This invention relates to analyzers. In another aspect, it relates to a method of controlling a crystal separation system.

Heretofore, considerable difficulty has been experienced in separating materials, such as isomers of xylene, particularly on a commercial scale. It has been found that these isomers can be separated by fractional crystallization but there is a problem in effecting adequate control of the crystal separation operation, particularly where a plurality of separate separation units are operated.

In accordance with this invention, crystal separation operations are readily and efficiently controlled, even where the operation takes place in a plurality of separate separation zones. More particularly, in accordance with the principles of this invention, a single control instrument is utilized in conjunction with a plurality of separate separation units by successively feeding streams to be analyzed from the separate units to a single differential refractometer wherein the refractive index of the sample is compared with that of a standard material to produce an output representative of the composition of the material being tested. Thereupon, the compositions of two or even more streams are indicated upon a single recorder chart, and the sample being analyzed is identified on the chart by forming an index mark thereon each time analysis of a different stream is initiated. Furthermore, by varying the length of the analyzing periods, the length of the trace on the recorder chart between consecutive index marks identifies the sample being analyzed during any particular period.

As will be evident from the foregoing, the control instrument is in itself novel by virtue of the marking circuits and provision for analysis periods of different duration, and such features have independent utility both in radiation analyzer instruments other than differential refractometers, and in the analysis or control of operations other than crystal separation.

Accordingly, it is an object of the invention to provide a radiation analyzer of improved character.

It is a further object to provide a method of controlling a crystal separation operation, particularly where the operation is carried out in a plurality of separate and distinct separation units.

Various other objects, advantages and features of the invention will become apparent from the following detailed description taken in conjunction with the accompanying drawings, in which:

Figure 1 is a schematic diagram of an analyzer constructed in accordance with the invention as applied to the control of a crystal separation operation; and

Figure 2 is a view of a recorder chart.

Referring now to the drawing in detail, and particularly Figure 1, we have shown a pair 10a, 10b of crystal separation units to which a feed stream including liquid and crystalline material is fed through conduits 11a and 11b, respectively. In each unit 10, a column of crystalline material is subjected to the action of a reciprocating piston 12a or 12b, and heat is supplied to the bottom of

2

each unit or column 10 by heating coils 13a and 13b, respectively. By the action of the piston and heating medium, a stream of liquid is displaced from each column of crystalline material, and these streams of displaced liquid are withdrawn through conduits 14a and 14b, respectively. Melt or product streams are withdrawn from the columns through the respective conduits 15a and 15b.

As one specific example of a separation which can be effected with the disclosed apparatus, the feed stream 10 can include mixed isomers of xylene in the crystalline form together with a liquid, which may include ethyl-benzene and toluene. The product stream consists of practically pure para-xylene while the displaced liquid withdrawn through the conduits 14 includes the ortho and meta-xylenes together with the ethyl-benzene and toluene.

Various other separations can be made in the columns 10, and reference is hereby made to the copending application of T. A. Tarr, filed June 21, 1954, Serial Number 438,051, for a description of a complete fractional crystallization operation together with a discussion of various separations which can be effected by this method.

As will become apparent hereafter, it is contemplated that more than two crystal separation units may be utilized. Where this is done, each column or crystallization unit is operated in the manner already described, with the product being withdrawn through a conduit 15, the displaced liquid being introduced through a conduit 14 and the feed being introduced through a conduit 11.

In the embodiment shown, portions of the product streams passing through conduits 15 are withdrawn and fed, in a cyclic manner, to a differential refractometer of novel construction. To this end, the conduits 15a, 15b are provided with restrictions 16a and 16b, respectively, 35 which are bypassed by lines 17a and 17b, respectively. Branching from the bypass lines are two sample inlet pipes or conduits 18a and 18b, respectively, which lead to a common sample inlet pipe 19. The pipe 19 leads to a sample cell 20a of a cell assembly 20, and the sample fluid, after passing through the cell, is withdrawn through a line 21. A standard fluid is introduced through a line 22 to a standard cell 20b of the assembly 20, and standard material is withdrawn from the cell through a line 23. The pressures in the two cells are equalized in any suitable manner, for example, by the pressure equalization device shown in the copending application of Bill J. Simmons, S.N. 264,515, filed January 2, 1952, now Patent No. 2,705,254.

A beam of radiation is produced by a source 24 which 50 is energized from terminals 24a under the control of a switch 24b. Where the instrument is a differential refractometer, as shown, source 24 can be an incandescent lamp emitting radiation in the visible wavelength range.

The source 24, therefore, produces a radiation beam 55 which passes through sample cell 20a and standard cell 20b to a rotatable reflector assembly 25 where it is reflected by prisms 25a, 25b and, thence, passes through a stationary prism 26 to a radiation detector unit 27 consisting of a pair of photoelectric cells 27a and 27b. 60 The action of the prism 26 is to direct a portion of the beam upon both the photoelectric cells 27, and the reflector assembly 25 moves, in the manner hereinafter explained, so as to deflect the beam and cause it to fall equally upon the two photoelectric cells. The beam deflection thereby produced balances the deflection produced as the beam passes through the material in cells 20a and 20b by virtue of the difference in the refractive indices of the fluids contained therein. That is, the amount of rotation of assembly 25 necessary to provide 65 a balance of the radiation incident upon the photoelectric cells is representative of the difference in refractive in-

70

dices of the test and standard materials and, hence, of the composition of the test material.

As will become apparent hereafter, the principles of the invention are applicable to radiation analyzers other than differential refractometers. Where other such instruments were used, source 24 is designed to provide the type of radiation, such as ultraviolet radiation or infrared radiation, which is desired, and the detector unit is designed to convert such radiation into an output representative thereof. For example, bolometers form a suitable detector unit for infrared radiation, and a photomultiplier tube is a suitable detector unit for ultraviolet radiation.

It will be noted that the photoelectric cells 27 are connected in opposition, and that the output of these photoelectric cells appears across two leads 28 and 29. Lead 29 is connected to a center tap on a primary winding of an input transformer 30a forming a part of an amplifier 30. The end terminals of this primary winding are connected to fixed contact points of a vibratory interrupter 31, the reed of which is connected to the common terminal of a two-position switch 32. One fixed contact of switch 32 is connected to lead 28 while the other fixed contact is connected through a battery 33 and a fixed resistance 34 to the lead 29.

With switch 32 in its upper position, as shown, leads 28 and 29 are connected through the interrupter 31 to the input circuit of the amplifier so that an alternating input voltage is produced which is representative of the relative amounts of radiation impinging upon the photoelectric cells 27. With switch 32 in its lower position, the photoelectric cells 7 are disconnected from the amplifier input circuit, and a constant voltage is applied thereto by the battery 33.

The output circuit of the amplifier 30 is connected to a servomotor 36 which is mechanically connected, as by a cam and cam follower, to the rotatable assembly 25. Thus, motor 36 rotates assembly 25 until the amount of radiation falling upon the photoelectric cells 27 is balanced, and the position of motor 36 and assembly 25 is representative of the beam deflection caused by the passage thereof through the standard and sample fluids, i.e., of the difference in refractive index of these fluids and the composition of the test material.

The motor 36 is also mechanically connected to the contactor of a potentiometer 37, a fixed direct voltage being supplied across the fixed terminals of this unit from a direct current source 37a. The contactor and one fixed terminal of potentiometer 37 are connected, respectively, to the input leads of a recorder 38 so that this unit records the refractive index or composition of the sample material, as indicated by the position of motor 36.

As previously explained, the sample inlet pipe 19 is connected to both sample conduits 18a and 18b through which the fluid to be analyzed flows from the columns 10a and 10b, respectively. Flow of fluid through conduits 18a and 18b is controlled by the respective solenoid valves 40a and 40b, the energizing windings of which are supplied with current from a set 41 of terminals through a timer or cam switch 42. The timer includes a motor 42a supplied with power from terminals 42b as controlled by a switch 42c. A shaft 42d is driven by the motor and carries a cam 42e which alternately closes two contact sets 42f and 42g, thereby alternately and cyclically opening solenoid valves 40a and 40b to permit fluid to pass to the sample cell alternately from the two crystal separation units.

Pilot lights 44a and 44b are connected in parallel, respectively, with the solenoids of valves 40a and 40b to indicate which valve is operating. A pair of time delay units or relays 45a and 45b have heater elements 46 connected in parallel with the respective solenoids of valves 40a and 40b. The time delay relays also have normally

closed contact sets 47a and 47b, respectively, which are connected in series with the respective operating windings of a pair of auxiliary relays 48a and 48b, the series combinations of relay winding and normally closed contact sets being connected in parallel with the respective solenoids of valves 40a and 40b. The contact sets 47a, 47b, each have a spark suppressor connected in parallel therewith, each suppressor including a resistance 49 and a condenser 50.

10 The relays 48a, 48b each have a set of normally open contacts which are connected in parallel. Closure of either contact set short circuits input leads 51 and 52 leading to the input terminals of the recorder 38.

In operation, timer 42 passes through repeated cycles 15 of operation, thereby alternately opening valves 40a and 40b. During each cycle, there is a period of analysis of fluid passing through line 18a and a period of analysis of fluid passing through line 18b. As these streams pass successively through the sample cell 20a, their composition

20 is indicated by recorder 38 by virtue of the action of servomotor 36, rotatable assembly 25 and potentiometer 37. The composition of the sample material is, accordingly, indicated upon the moving recorder chart or medium, Figure 2, in an alternating manner, the composition 25 of the fluid passing through line 18a being indicated by portions 55a of the chart, and the composition of the fluid passing through line 18b being indicated by portions 55b of the chart.

It is a feature of the invention that the cam 42e of timer 30 42 is so shaped that one of the recording periods is longer, to a slight but noticeable extent, than the other recording period. Accordingly, one set 55a of traces upon the recorder chart is longer than the other set 55b, thus enabling the operator to determine at a glance 35 which stream is represented by any part of the line on the chart.

Further, as each valve 40a or 40b is opened at the beginning of an analyzing period, current is supplied 40 through the associated contacts 47 to the associated relay 48, thereby energizing one of these relays, and closing one set of relay contacts to short circuit the amplifier input leads. This causes the pen on the recorder chart to move to zero, as indicated by the lines 55c in Figure 2, thereby forming an index mark on the chart each time 45 analysis of a different stream is initiated.

Closure of the circuit through one of the solenoid valves also closes a circuit through the associated heater element 46, which causes the associated contact set 47a to open after a short predetermined period, as determined 50 by the setting of the time delay unit. Thereupon, the associated relay 48 is deenergized and its contacts are opened thereby opening the short circuit existing at the recorder input terminals. At this time, the recorder pen returns to its normal recording position 55a, 55b and indicates the composition of the fluid under analysis 55 during the remainder of the analysis period.

In addition to providing a short index mark on the chart at the beginning of each analysis period, the described deactivation of the recorder is advantageous for, during this short interval, the new material to be analyzed passes through conduit 19 and reaches the sample cell 20a before operation of the recorder is initiated to indicate the composition of this new test material.

It will be evident, therefore, that we have achieved the 60 objects of the invention in providing an instrument well suited for the analysis of multicomponent streams, the recorder chart permitting the stream under analysis to be accurately and rapidly identified, and having an index mark at the beginning of each analysis period. Moreover, the instrument is adapted to indicate the composition of one of the feed displaced liquid, product or heating medium streams of a crystal separation operation, particularly one involving a plurality of distinct separation units, to the end that proper and efficient process 70 control can be maintained.

Also, in accordance with the invention, the described differential refractometer can advantageously be used to control a crystal separation process, even where a single instrument is used for this purpose in conjunction with a plurality of separation units. To this end, we have shown the system applied to the automatic control of two columns to regulate the rate of flow of product from the separation units in accordance with the composition of the product stream. It will be understood, of course, that under different conditions the composition of other streams can be determined and other process variables can be regulated than the rate of flow of product. For instance, the feed rate can be regulated, or the rate of withdrawal of displaced liquid, or even the quantity or temperature of the heating medium supplied to the coils 13 in a manner which will become obvious upon reading the following description.

In the described embodiment, an additional cam 60 is provided on cam shaft 42d, and this cam actuates contact sets 60a and 60b. Contact set 60a is closed a predetermined period after the closure of contact 42f, the delay period being allowed to permit fluid from line 18a to reach the sample cell 20a before the control period is started. Further, contacts 60a open at the same time as contacts 42f. Similarly, contact set 60b closes a predetermined interval after the closure of contact set 42q and opens at the same time as contact set 42g.

Contact sets 60a and 60b are operative to connect the voltage applied to the recorder input terminals to an electronic rate of flow controller 61 when valve 40a is open and to an electronic rate of flow controller 62 when valve 40b is open. The controllers 61 and 62 have the usual flow-sensing taps in the lines 15a and 15b, respectively, and they control valves 64a and 64b, respectively, so as to maintain the product of the two columns at a constant refractive index, i.e., composition. The controllers remain at the position they reach at the end of a control cycle until the beginning of the next control cycle and, in commercial units, the product composition changes with sufficient slowness to permit efficient operation, even though the actual control is being effected during slightly less than half the time of operation.

While the invention has been described in connection with a present, preferred embodiment thereof, it is to be understood that this description is illustrative only and is not intended to limit the invention.

We claim:

1. In a separation process utilizing crystals wherein, in each of a plurality of separation zones, a feed stream including crystalline and liquid material is fed to the separation zone, a liquid stream is displaced and separated from the feed stream, and crystals are melted to form a product stream by exchange with a stream of heating medium, the steps which comprise withdrawing a first portion of a stream from one of said separation zones, forming a beam of radiation, producing an output representative of the deflection of a terminal part of said beam, passing said first portion through said beam to cause a deflection thereof representative of the index of refraction of said first portion, the output thereby produced representing the stream composition, withdrawing a second portion of a stream from another separation zone, passing said second portion through said beam after interrupting the flow of said first portion therethrough, whereby a beam deflection is produced which is representative of the composition of said second portion, and thereafter alternately and cyclically passing portions from said separation zones through said beam.

2. A method in accordance with claim 1 wherein said first portion is passed through the beam for a longer period, during each cycle of operation, than is said second portion.

3. In a separation process utilizing crystals wherein, in each of a plurality of separation zones, a feed stream including crystalline and liquid material is fed to the

separation zone, a liquid stream is displaced and separated from the feed stream, and crystals are melted to form a product stream, the steps which comprise passing a beam of visible light through a standard fluid to cause a deflection thereof, producing an output representative of beam deflection, recording said output upon a moving medium, cyclically withdrawing a stream, in succession, from each separation zone to provide, during each cycle, at least a first analyzing period and a second analyzing period, and passing the withdrawn streams during the respective analyzing periods through said radiation beam to further deflect same.

4. In a separation process utilizing crystals wherein, in each of a plurality of separation zones, a feed stream including crystalline and liquid material is fed to a separation zone, a liquid stream is displaced and separated from the feed stream, and crystals are melted to form a product stream, the steps which comprise passing a beam of visible light through a standard fluid to cause a deflection thereof, producing an output representative of beam deflection, recording said output upon a moving medium, cyclically withdrawing a stream, in succession, from each crystal separation zone to provide, during each cycle, at least a first analyzing period and a second analyzing period, said first analyzing period being of longer duration than said second analyzing period, passing the withdrawn streams, during the respective analyzing periods, through said radiation beam to further deflect same, and producing an index mark upon said medium at the beginning of each analyzing period.

5. An analyzer for analyzing a plurality of sample streams to be analyzed which comprises, in combination, a radiation source, a radiation detector unit disposed in the beam of radiation from said source, a recorder

35 having a set of input terminals, means responsive to radiation impinging on said detector unit for applying to said recorder input terminals a signal representative of the radiation impinging upon said detector unit, a first line arranged to deliver a first sample stream into the beam of radiation, a first solenoid valve controlling the flow of stream through said line, a second line arranged to deliver another sample material into the beam of radiation, a second solenoid valve controlling the flow of material through said second line, first and second 40 relays each having an operating winding and a set of contacts connected in circuit with the input terminals of said recorder, each contact set being arranged to apply a signal to the recorder upon energization of the relay controlling the set of contacts, a timer arranged to alternately energize said solenoid valves, first and second time delay devices connected in circuit with the respective solenoid valves and energized by said timer at the time of energization of the respective solenoid valves connected thereto, and connections between said time 45 delay devices and the operating windings of the respective relays, said connections being arranged so that each relay is energized upon energization of the time delay device connected thereto and de-energized a predetermined time thereafter.

6. An analyzer for analyzing a plurality of sample streams to be analyzed which comprises, in combination, a radiation source, a radiation detector unit disposed in the beam of radiation from said source, a recorder having a set of input terminals, means responsive to radiation

65 impinging on said detector unit for applying to said recorder input terminals a signal representative of the radiation impinging upon said detector unit, a first line arranged to deliver a first sample stream into the beam of radiation, a first solenoid valve controlling the flow of material through said line, a second line arranged to deliver another sample stream into the beam of radiation, a second solenoid valve controlling the flow of material through said second line, first and second relays each 70 having an operating winding and a set of contacts connected in circuit with the input terminals of said recorder,

each contact set being arranged to apply a signal to the recorder upon energization of the relay controlling the set of contacts, a timer arranged to cyclically and alternately energize said solenoid valves, first and second time delay devices connected in circuit with the respective solenoid valves and energized by said timer at the time of energization of the respective solenoid valves connected thereto, connections between said time delay devices and the operating windings of the respective relays, said connections being arranged so that each relay is energized upon energization of the time delay device connected thereto and deenergized a predetermined time thereafter, the time of energization of one of said solenoid valves during each cycle being greater than the time of energization of the other solenoid valve.

7. A multistream differential refractometer which comprises, in combination, a photoelectric cell detector unit, a source of visible light arranged to direct a beam of radiation upon said detector unit, a recorder connected to and energized by said detector unit, timing means arranged to cyclically admit, in succession, a plurality of sample streams to the path of said beam to provide a plurality of analysis periods during each cycle, whereby said beam is deflected and the recorder produces an output representative of beam deflection, and means energized by said timing means to apply a signal to said recorder at the beginning of each period of analysis, whereby an index mark is made by the recorder signifying the beginning of each analysis period.

8. A multistream differential refractometer which comprises, in combination, a photoelectric cell detector unit including a pair of spaced photoelectric cells, a source of visible light arranged to direct a beam of radiation upon said photoelectric cells, a prism arranged in said beam to disperse same and cause it to fall upon both photoelectric cells, motor-driven means to deflect said beam, a cell assembly in the path of said beam including a standard cell and a sample cell, a plurality of lines arranged to deliver different sample streams to said sample cell, solenoid valves controlling the flow of fluid through the respective lines, a time delay relay connected in parallel with each solenoid valve, a plurality of auxiliary relays having their operating windings connected in circuit with the respective time delay relays to the end that the auxiliary relays are energized upon the energization of the respective time delay relays and deenergized a short period thereafter, each auxiliary relay having a set of contacts controlled thereby, a timer, means controlled by said timer to alternately and cyclically open said solenoid valves and energize the time delay relays connected thereto, a recorder having a set of input terminals, a potentiometer connected to said input terminals to provide an input signal for said recorder, leads connecting said input terminals to the contacts of each auxiliary relay whereupon energization of each auxiliary relay short circuits the recorder input terminals, a mechanical coupling connecting said motor-driven means to said potentiometer, an alternating current amplifier having its output circuit connected to said motor means to energize same, and means including a vibratory interrupter for connecting said photoelectric cell detector unit to the input of said amplifier.

9. A multistream differential refractometer which comprises, in combination, a photoelectric cell detector unit, a source of visible light arranged to direct a beam of

radiation upon said unit, motor-driven means to deflect said beam, a cell assembly in the path of said beam including a standard cell and a sample cell, a plurality of lines arranged to deliver different sample streams to said sample cell, solenoid valves controlling the flow of fluid through the respective lines, a time delay unit for each valve, a timer, means controlled by said timer to alternately and cyclically open said solenoid valves and energize the time delay units corresponding thereto, a recorder, a potentiometer connected to the input of said recorder to provide an input signal, means connecting said recorder to said time delay units to apply a signal thereto during the delay period of each such unit, a mechanical connection between said motor-driven means and said potentiometer, an alternating current amplifier having its output circuit connected to said motor means to energize same, and means including a vibratory interrupter for connecting said detector unit to the input of said amplifier.

20 10. In a control system, for a plurality of separation units utilizing crystals wherein, in each of a plurality of separation zones, a feed stream including crystalline and liquid material is fed to the separation zone, a liquid stream is displaced and separated from the feed stream, and crystals are melted to form a product stream, in combination, a differential refractometer, means including a timer for cyclically feeding samples of the product streams of the plurality of separation zones, in succession, to said refractometer, electrically actuated controllers arranged to regulate the rate of withdrawal of product from the respective separation zones, and means actuated by said timer for feeding the output of said refractometer to the controller of the rate of product withdrawal of that separation zone from which the sample material is being fed to said refractometer.

11. A multistream differential refractometer which comprises, in combination, a photoelectric cell detector unit, a source of visible light arranged to direct a beam of radiation upon said unit, motor-driven means to deflect said beam, a cell assembly in the path of said beam including a standard cell and a sample cell, a plurality of lines arranged to deliver different sample streams to said sample cell, valves controlling the flow of fluid through the respective lines, a time delay unit for each valve, a timer, means controlled by said timer to alternately and cyclically open said valves and energize the time delay units corresponding thereto, means connecting said recorder to said time delay units to apply a signal thereto during the delay period of each such unit, and means connecting said detector unit to the input of said recorder to produce a signal representative of the amount of light falling upon said photoelectric cell detector unit.
